SEWING MACHINES

Paul O. Rutishauser, Wil, Switzerland, assignor to Regina Sewing Machines Corporation, New York, N.Y.

Filed May 14, 1954, Ser. No. 429,880

Claims priority, application Switzerland May 30, 1953

5 Claims. (Cl. 112—158)

This invention relates to a so-called zig-zag sewing machine having a free arm containing a looper for cooperating with a reciprocable needle, which is swingable to and fro at right angles to the material feeding device.

The present invention is characterized by the incorporation of two disengageable control cams, each of which is adapted to act on the needle swinging mechanism and being movable about a common axis by hand, one control cam serving to adjust the extent of the reciprocal deflection of the needle for zig-zag switching, and the other serving to adjust the needle for lateral displacement of the sewing axis; and an insertable double-control cam for effecting the same adjustments automatically, the whole arrangement being such that the hand or automatic control elements may be selected for operation, as desired.

A zig-zag sewing machine constructed in accordance with the invention is illustrated in the accompanying drawings, by way of example.

In said drawings:

Fig. 1 is a front view of the machine with the front wall removed and its driving wheel being shown in section.

Fig. 2 shows the driving wheel with a winding pin in outwardly projected position.

Fig. 3 is a plan view of the mechanism for adjusting the length of stitch.

Fig. 4 is a view taken on line IV—IV, Fig. 1.

Fig. 5 is a side view of the control means with cams inserted for automatic control;

Fig. 5a is a sectional view of the control means of Fig. 5, showing the normal condition of the machine for manual control.

Fig. 5b is a sectional view of the control means of Fig. 5 with the cam discs for automatic zig-zag operation in position;

Fig. 5c is a front view of the hinged cover and associated elements;

Fig. 6 is an external view of the hand-operable control members;

Fig. 7 is an exploded view of the handwheel, knurled nut, and winding pin mechanism of Fig. 2;

Fig. 8 is a sectional view of the worm wheel and cams, showing the splines serving as clutch means; and

Fig. 9 is an elevation view of a portion of the drive mechanism showing the meshing gears and drive shaft.

Referring now to said drawings, 1 denotes a casing comprising an upper part, lower part, and base plate. Located in the lower part of said casing, and secured to the base plate, is a driving motor 2 which also includes a transformer for supplying lighting current. On the driving shaft 3 of motor 2 is secured a roughened wheel 4 which engages in a co-axial groove 6 formed in hand wheel 5. The outer wall of groove 6 is also provided with a roughened surface. Rotatably mounted on hand wheel 5 is a knurled nut 7 which internally accommodates a cam groove 8. A winding device consisting of a disc 9, two pins 10, and a winding pin 11, is located within hand wheel 5 and nut 7, and, by means of a sliding element 9a on its periphery, is in engagement with said cam groove 8 (Fig. 7).

Furthermore, disc 9 is provided, on its side facing

2

casing 1, with radial grooves 12 which, when winding pin 11 is in operative position (as shown in Fig. 1) engage with co-operating raised ribs 13 provided on the end face of shaft 14. Displacement of said winding device is effected by turning nut 7 by hand opposite the direction of rotation of hand wheel 5, whereby cam groove 8 effects displacement of the winding device 9, 10, 11, which, by reason of its pins 10, is not rotatable relative to hand wheel 5.

10 Said shaft 14 serves, by the aid of a gear wheel 15, to drive a looper 16 and to control the movement of a material feeding or advancing device 17 which is capable of two movements, viz: an up-and-down movement for gripping and releasing the material, and a horizontal movement for the advancement of the material. Said material feeding device 17, which is grooved at 18, is pivotally movable in an upward direction about an axis 19. A pin 20, which rests on an eccentric 21 of shaft 14, transmits the required lift. The extent of the small reciprocal rotary movement of a shaft 22, which is imparted to the material feeding device by way of a lever 23, is governed by the position of a grooved element 24 adjustable by means of the lever 25, via shaft 26.

Located on said lever 25 is a screw 27 projecting from the casing of the machine. The screw, when not under any external influence, bears against the left hand side of an angled stop plate 29 due to the tension of a bias spring 28.

A grooved block 30 connected to a fork 69 engages in the groove of member 24; and the movement of said fork is primarily effected by an eccentric 31 on shaft 14 and, secondly, by the position of the grooved member 24. By the up and down movement of the left hand part of fork 69 (Fig. 4), a swinging movement about the axis of shaft 22 is imparted to the right hand part of the fork, which movement is transmitted to shaft 22 by way of arms 32. This movement produces the advance and return motion of the material feed device 17. Rotation of shaft 14 and cam 31 mounted thereon causes a swinging motion to take place in fork arm 69 in a direction and amplitude which is controlled by the position of block 30 and its groove 24 in which a pin connected to fork arm 69 is slideably guided. Reciprocating movement of fork arm 69 is transmitted through arms 32 to shaft 22 to member 23 and thence to material advancing device 17. If lever 25, by manipulation of screw 27 from the outside, is caused to bear against the right hand side of the stop plate 29, then the grooved member 24 is turned around, and the material being sewn is fed in the reverse direction without necessity for reversing the direction of rotation of shaft 14. The extent of the feed per stitch (one revolution of the shaft 14) is effected by adjustment of screw 27, with consequential displacement of the stop position on plates 29. The arrangement shown in the drawing allows an accurate adjustment of the length of stitch and an immediate change-over to sewing in a reverse direction when desired, with the same length of stitch. Members (not shown) are adapted to engage pin 20 and release it from the influence of eccentric 21, whereby the material feed device 17 is lowered into the casing and discontinues to feed the material. The engagement and disengagement of pin 20 may be effected by hand or automatically, on attaching a darning plate.

65 A shaft 34 is driven by shaft 14 by way of a belt 33, whereby the up and down movement of a needle bar 35 with a needle 36 is effected by means of an eccentric 37 and links 38, 39, 40. Said needle bar is supported and guided by a frame 41 which is adapted to swing about a point 42, and the control of this swinging movement, inter alia, sets the standard for the type of stitch which

has been selected. Shaft 34 drives, by way of a worm 43, a wheel 44 fixedly mounted on a hollow shaft 45. The end face of shaft 45 adjacent the front of the machine is provided with radial splines 46 so as to form a first clutch means. For the automatic adjustment of the needle bar, there are provided two cam discs 47 and 48, which are mounted on a shaft 49 fitted in the hollow part of shaft 45. Radial grooves or splines 50 of the cams form a second clutch means and mesh with the first clutch means, i.e. the splines 46 of said shaft 45. 10

Said cam disc 47 functions to adjust the sewing axis of the needle. By means of a spring 51a, a lever 51, with an adjustable pin 52 bears against cam disc 47 and pivots about a point 53. Pin 52 (Fig. 1) is threadedly engaged in arm 51 and may be turned to adjust its protruding length from arm 51 to the cam face of cam 47. Pivotedly mounted on lever 51 is a grooved member 54 whose movement is effected by a cam-follower block 57 rotatably disposed thereon and engaging in a cam groove 55 of a roller 56. Said roller 56 is driven from shaft 34 by way of gear wheels 58, 59, the latter of which is located on the same shaft 60 as the roller 56. The movement of member 54 is transmitted, by way of a grooved block 62 which slides in the groove 61 of member 54, to a lever 63 which, in turn, imparts movement to the needle bar frame 41.

Cam disc 48 serves to automatically adjust and vary the overstitch width for the zig-zag operation by controlling, through pin 64, the movement of a bifurcated lever 65 which acts directly on lever 63 and, as far as necessary, effects the displacement of grooved block 62 in groove 61.

Fig. 5a illustrates the normal condition of the sewing machine, in which the zig-zag width adjustment as well as the needle position may be adjusted by hand. By swinging the cover 66 (shown in Fig. 5c) outwardly, together with the handwheels 67 and 68, the cam discs 47, 48 for automatic zig-zag operation can then be inserted, as shown in Fig. 5b. By swinging the cover 66 back into position, the discs 47a and 48a are pushed outwardly, i.e. toward the left in Fig. 5b, in opposition to the spring, so that the handwheels 67, 68 protrude somewhat from the cover 66. Fig. 5c shows a front view of the cover 66 and elements 67, 68.

Cam discs 47, 48 may be of diverse shapes and may be changed as desired. In order to use the sewing machine only for hand control, the two cams 47 and 48 are removed and replaced by the cams 47a and 48a (Fig. 4) which are rotatably mounted on a hinged cover 66. These two cams 47a and 48a are operably connected with members 67, 68, respectively, which are hand-actuable externally of casing 1, and adjustment or displacement of the cams is not affected by rotation of shaft 45. A segment 70 must be raised in order to permit opening of cover 66, and a rod 71 secured to segment 70 is raised simultaneously. Said rod 71 engages levers 51 and 65 and disengages them from the cam discs 47 and 48 or 47a and 48a, respectively, so that new cams may be readily inserted. In other words, as best shown in Fig. 1, the rod 71 serves as a transverse lifting bar to engage levers 51 and 65 (which normally press against the cam discs with their respective pins 52 and 64), so as to lift these levers away from the cam discs when the latter are being exchanged. A spring 75 (Figs. 5a and 5b), disposed between cover 66 and cam disc 48a, ensures that the cams are always in register with the appropriate levers 51 and 65.

The sewing area is illuminated by a small lamp (not shown) which is accommodated in the cover in front of the needle bar frame 41, its light shining through openings in the cover. The cover plate of the free arm of the looper is removable and replaceable by a darning plate. In other respects, the machine embodies the usual attachments, such as an extension support for the material, thread guides, and interchangeable presser foot members.

I claim:

1. A zig-zag sewing machine, comprising a housing having a free arm and having a needle bar reciprocable from above toward and away from said arm and swingable horizontally, a mechanism operatively connected with said needle bar for imparting swinging movement thereto, control means linked with said mechanism for controlling said mechanism, said control means having two coaxial cams manually rotatable for controlling the amount and position of said swinging needle-bar movement respectively, said two cams being selectively engageable and disengageable relative to said mechanism, and a pair of cams for automatic control of said amount and said position respectively, said cam pair being selectively insertable and being linked with said mechanism when said manually controllable cams are disengaged, and drive means for rotating said cam pair in dependence upon operation of said needle bar, whereby the machine can be set selectively for manual and automatic control operation.

2. In a zig-zag sewing machine having a needle bar reciprocable up and down and swingable horizontally, the combination with said sewing machine of a material feeding device comprising a material-entraining part located beneath said needle bar and displaceable horizontally to vary the stitch length, a lever connected with said part and having an adjustable set screw, an angular stop member, said lever being spring biased toward engagement of said screw with said stop member, whereby the adjusted setting of said screw determines the stop position of said lever and part and thus the length of the stitches.

3. In a sewing machine according to claim 1, comprising a first lever having one end pivoted and having the other end bifurcated, said first lever being in engagement with the one of said cams of said pair serving for the control of the amount of swinging needle-bar movement, said mechanism having a second lever linked with said needle bar, a roller having a cam slot, a grooved member slidably in said slot, said second lever being linked with said grooved member whereby the position of said member determines the stitching position, a medially-pivoted third lever having one end linked to said grooved member and having the other end in engagement with the other cam of said pair to be controlled thereby.

4. A sewing machine according to claim 1, comprising a motor-driven main shaft, said drive means for rotating said cam pair having a drive shaft, a belt transmission connecting said drive shaft with said main shaft, a worm mounted on said drive shaft, a gear meshing with said worm, first clutch means on said gear, and said pair of cams being co-axially mounted relative to said gear and having second clutch means in clutching engagement with said first clutch means.

5. In a sewing machine according to claim 1, a cover hinged to said housing, said two manually operable cams being mounted on said cover, said control means having respective cam-follower levers engaging said respective two cams when said cover is in closed position and being disengaged from said cams when said cover is in open position, and said automatic cam pair being insertable only when said cover is open and said manual cams are disengaged.
